UNITED STATES PATENT OFFICE.

GEORGE F. CRIPPEN, OF YPSILANTI, MICHIGAN, ASSIGNOR TO THE CRIPPEN MANUFACTURING COMPANY, OF MOUNT PLEASANT, MICHIGAN, A CORPORATION OF MICHIGAN.

ROLL-ADJUSTING APPARATUS.

1,352,052.

Specification of Letters Patent. Patented Sept. 7, 1920.

Application filed May 9, 1918. Serial No. 233,519.

To all whom it may concern:

Be it known that I, GEORGE F. CRIPPEN, a citizen of the United States, residing at Ypsilanti, in the county of Washtenaw and State of Michigan, have invented certain new and useful Improvements in Roll-Adjusting Apparatus, of which the following is a specification, reference being had therein to the accompanying drawing.

10 This invention relates to a roll adjusting apparatus, which, while susceptible of a wide variety of uses, is more especially adapted for use in connection with machines wherein is employed a series of pairs of rolls 15 radially arranged, the rolls of each pair being adapted to rotate relative to one another, and it is the primary object of the invention to provide novel and improved means whereby the rolls of each pair or set may be adjusted laterally relative to one another, to accurately regulate or change at will the space between the rolls.

Heretofore, it has largely been the custom, when desired to relatively adjust the rolls 25 of a plurality of sets or pairs, to independently adjust one or both of the rolls of each pair. This is objectionable because of the expense incident to the provision of independent adjusting means for each pair of 30 rolls, and also because of the loss of time and labor in making the necessary adjustment. Then again, there is the further very decided and serious objection that the various pairs of rolls will oftentimes not be accurately or harmoniously adjusted with the 35 result that the rolls of one pair will be relatively spaced a certain distance, whereas the rolls of succeeding pairs will be relatively spaced different distances, thereby 40 involving a non-uniform action by the respective pairs of rolls on the material operated upon thereby.

One of the underlying purposes of the 45 present invention may be said to reside in the provision of means of novel and efficient construction whereby the rolls of a plurality of annular series of pairs, may be quickly, accurately, and simultaneously adjusted, through the medium of a key actuating and 50 adjusting means, thereby resulting in the saving of time, expense, and uniform adjustment with regard to the rolls of the entire series.

Further, the invention involves means operatively associated with the adjusting mechanism just described whereby, after adjustment, the rolls will be maintained or locked in a fixed relative position, and means whereby said locking means may be readily released, to permit of further adjustment at will.

In the preferred embodiment of the invention herein illustrated, an annular or concentric series of radially disposed rolls are employed, the rolls being arranged at a slight inclination from the horizontal, and the rolls being arranged in pairs, with the rolls of each pair adapted to rotate and co-operate one with the other to draw material therebetween, and to permit such material as is not drawn therebetween to discharge from the lower ends of the rolls. For one of the rolls of each pair, there is provided an eccentric bushing, which, upon being turned in its bearing, is adapted to move its connected roll away from the co-operating roll, and it is contemplated by the present invention to provide means whereby the eccentric bushings of the respective adjustable rolls may have simultaneous rotatable movement imparted thereto to relatively adjust the rolls.

Still further, it is an object of the invention to provide a roll adjusting device, simple in design and construction, comparatively inexpensive to produce, highly efficient in operation, and strong and durable in service.

Still other and further improvements and novel details in the construction and arrangement of the various parts of the invention will be appreciated from the description to follow, which, for a clear and comprehensive understanding of the invention is to be considered in connection with the accompanying drawings which form a part hereof, and wherein is disclosed for the purpose of illustration, a convenient and satisfactory embodiment of the invention. In this connection, however, it is to be borne in mind that many minor changes and slight modifications in the structural details and arrangement of parts may be made, and still be within the spirit of the invention.

In the drawings: 105
Figure 1 is a vertical section, of an ap-

paratus, broken away, with my roll adjusting mechanism or apparatus applied thereto:

Fig. 2 is a top plan view, with parts removed;

Fig. 3 is a vertical section, with parts broken away.

Fig. 4 is a detail view enlarged of the roll adjusting shaft and associated parts;

Fig. 5 is a detail view enlarged of one of the adjustable rolls.

With more particular reference to the drawings, wherein like reference numerals refer to corresponding parts throughout the several views, 1 is a suitable casting, conveniently sleeved upon a central vertical shaft 2 for rotatable movement. The casting 1 may rotate in any desired manner as through the medium of a hub 3 sleeved upon the shaft and having a connected gear 4 adapted to mesh with, and be driven by, a suitable drive pinion 4^a, the latter being driven from any suitable source. The hub 3 also connects through the medium of a spider or web frame 3^a with an inner annular supporting frame or ring 5, as through the medium of detachable bolts 6.

Conveniently the casting is provided with a plurality of curved chutes or channels 7 leading from a suitable hopper 7^a, whereby to discharge material to be operated upon, through the channels to the rolls to be presently described. Connecting with webs 3^a is an auxiliary annular supporting ring 5^a spaced outwardly from the supporting ring 5. Interposed between the inner and outer supporting rings 5 and 5^a are the operating rolls arranged in pairs, one of the rolls of each pair, 12, being adjustable laterally with respect to its coöperating roll 13, which latter is preferably fixed in position. The rolls 12 and 13 are conveniently arranged upon a slightly different relative horizontal plane, as illustrated.

The rolls 12 and the mechanism for adjusting the same, are preferably constructed substantially as follows:

The annular supporting rings 5 and 5^a have openings therethrough adapted for the reception of bushings. A rod or bar 9 projects between the bushings and is secured to the latter in any desired manner, as by headed bolts 10 projecting through apertures in the bushings, and engaging recesses in said rod 9. Loosely positioned on the rods 9 are sleeves 11 adapted to support the rolls 12 proper, which latter are formed of rubber, or other suitable material. The bushings 8 and 8^a have suitable eccentric recesses adapted for the reception of the ends 11^a of the sleeves 11. Positioned on the sleeves 11 are suitable pinions or gears 13^a adapted to engage a coöperating pinion or gear 13^b of the coöperating fixed roll 13, in an obvious manner.

From the description thus far, it will be appreciated that upon rotating an inner bushing 8 in its bearing in the inner annular supporting ring 5, the outer bushing 8^a because of the fixed connection provided by the rod 9, will have simultaneous rotatable movement imparted thereto in its bearing. This rotatable movement of the bushings 8 and 8^a respectively will result in adjusting or positioning the coöperating rolls 12 and 13 of a pair of such rolls either closer together or farther apart, according to the direction of rotation of the bushings.

As previously noted, it is desirable to simultaneously adjust the bushings of a plurality of the adjustable rolls, and to this end, upon each of the inner bushings 8, conveniently at or adjacent the inner end thereof, is a fixed pinion or gear 14, preferably formed by teeth cut only partially therearound. These teeth are adapted to mesh with teeth 15^a upon the upper surface of a master adjusting gear ring 15, the teeth being arranged adjacent the periphery of said ring, and the ring being supported in any desirable manner for rotatable movement, as by a hub 15^b sleeved upon the shaft 2. The adjusting gear ring 15 has upon its under surface adjacent the periphery thereof, a series of teeth 16, the teeth being cut for a relatively short distance, being sufficient in number to correspond with those upon a pinion 17 fixed to rotate with a suitable substantially horizontally extending shaft 18 having suitable bearings 19 and 20 in the casting 1, and terminating at the outer end thereof in a suitable head 21 adapted to receive a wrench or other operating tool. By imparting rotatable movement to the shaft 18 through the medium of the operating head 21 in one direction or the other, the pinion 17 will be correspondingly rotated whereby to impart rotatable movement to the gear ring 15, the movement being limited in any desired manner, as by the number of teeth 16-17.

In order that the operator may be advised as to the exact adjustment, it being essential in the treatment of certain materials to have this adjustment as predetermined and accurate as possible, there is provided a sleeve 22 fixed to the shaft 18 in any desired manner, and having upon the periphery thereof any suitable indicating data, adapted to register in the rotatable movement of the shaft and provided with an indicating point 23 positioned on the fixed bearing 20 for the shaft 14. In this way it is possible for the operator to know at all times the exact adjustment to which the rolls have been subjected. After the adjustment has been made, it is desirable to retain the locking parts against accidental adjustment, and to this end a suitable lock nut 24 is provided, the same having a

threaded engagement with the shaft 18 whereby to abut against that side of the bearing 23 opposite that side engaged by the sleeve 22. When the locking nut 24 is 5 tightly engaged with the bearing 23 any accidental movement of the shaft 18 and associated gear connections will be prevented, whereas when the end 24 is loosened by a reverse turning movement on the 10 threads of the shaft 18, the latter will be free for rotatable movement which in turn will impart through the gearing connections the necessary adjustable movement for changing the relative position of the rolls. 15 As has been appreciated, the head 1 and parts connected therewith, including the hub 3, the separating rolls 12 and 13, etc., are adapted to be rotated about the shaft 2 through the medium of the drive pinion 20 4^a, which meshes with the gear 4 mounted upon the hub 3. As the head and parts connected therewith rotate, it is desired to impart rotatable movement to the rolls 12 and 13 about their longitudinal axes, and with 25 this in view, the fixed master gear 25 is provided, the same being keyed or otherwise fixed as at 26 to the shaft 2 and having upon the upper surface thereof adjacent the periphery a circumferential series of teeth 30 27 to be engaged by a pinion 28 fixed upon a projecting end of each of the fixedly mounted rolls 13.

Because of the intermeshing gears 13^a and 13^b on the rolls 12 and 13 respectively, it 35 will be observed that as the head 1 and associated parts are rotated the pinions 28 will be rotated by reason of engagement with the master gear 25 which will in turn impart rotatable movement to the rolls 13 in 40 one direction and rotatable movement to the adjustable roll 12 in an opposite direction. Should it be desired to remove the head, including the trough 7^a, feed chutes, etc., of the casting, whereby to obtain access to the 45 rolls for repair, cleansing, etc., the operator removes the bolts or other securing means 29, when the head may be removed.

The entire operation may be briefly reviewed as follows: 50 Assuming that the shaft 2 is stationary, the head 3 is rotated from any suitable driving source through the medium of the gears 4-4^a whereby to impart rotatable movement about the shaft 2 to the casting 1 and the parts mounted thereupon, including the 55 separating rolls 12-13. In such rotatable movement each driving roll, 13 will be engaged through the medium of its pinion 28 by the stationary master gear 25 whereby 60 these rolls are rotated and through the medium of the intermeshing gears 13^a, 13^b, the coöperating or adjustable rolls are rotated. The material to be operated upon being delivered into the hopper 7^a will pass 65 through the feed chutes 7 into operative po-

sition relative to the circumferential series or pairs of rolls 12-13, the separated material passing between the rolls 12-13, and the material which does not pass between the rolls finding a point of discharge at the 70 lower end of said rolls, the rolls being inclined whereby to assist the feeding movement of the material. As it becomes necessary to relatively adjust the rolls 12-13, it being borne in mind that it is quite important 75 that all of the rolls 12-23 being simultaneously uniformly adjusted, the lock nut 24 is moved to releasing position whereupon the head 21 of the adjusting shaft 18 may be engaged by a wrench or other suitable tool to impart the necessary rotatable movement to the shaft 18. In the rotatable movement, the operator is guided by the indicating data as illustrated at 22-13 whereby at all times the degree of adjustment is 80 accurately determined. The rotation of the shaft 18 through the medium of the pinion 17 thereupon engages the master adjusting gear 18, which will through the medium of the coöperating gears 14-15^a impart the 85 necessary rotatable adjustable movement to the eccentric bushings of the rolls 12 thereby moving said rolls either toward, or away from, the fixed coöperating rolls 13.

In view of the fact that the number of 90 teeth 16 upon the under surface of the master adjusting gear 15 is limited, it will be appreciated that as the adjusting shaft 18 is rotated, the movement of the master adjusting gear 15 is limited, in opposite directions, determined upon the number of said 95 teeth 16.

What I claim is:

1. In an apparatus of the character described, the combination of an annular series of rotatable rolls arranged in pairs, one of the rolls of each pair being laterally adjustable relative to the other, and means arranged within the space at the inner ends of the series of rolls, forming driving 105 means common to all of the adjustable rolls for simultaneously adjusting the same.

2. In an apparatus of the character described, the combination of an annular series of rotatable rolls arranged in pairs, one 110 of the rolls of each pair being laterally adjustable relative to the other, a rotatable gear ring having a direct gear connection with all of the adjustable rolls for simultaneously adjusting the rolls, and means co- 115 operating with the last mentioned means for locking the adjustable rolls in adjusted 120 positions but free to rotate.

3. In an apparatus of the character described the combination of an annular series of radially disposed rolls, the rolls being arranged in pairs, and the rolls of each pair being adapted to oppositely rotate, one of the rolls of each pair being adapted to be 125 bodily adjusted laterally, and manually op- 130

- erable gear mechanism associated with all of said adjustable rolls, whereby to simultaneously move the same to increase or diminish separation between the rolls of each pair.
5. 4. In an apparatus of the character described, the combination of a pair of coöperating rolls, an eccentric support for one of said rolls, a gear on said support, and a coöperating gear for imparting rotatable movement to the first mentioned gear and connected support, whereby the rolls may be variably positioned relative to one another.
10. 5. In an apparatus of the character described, the combination of a pair of coöperating rolls, an eccentric support for one of said rolls, a gear on said support, and a coöperating gear for imparting rotatable movement to the first mentioned gear and connected support, whereby the rolls may be variably positioned relative to one another, a hand control for said coöperating gear, and operatively associated indicating means for determining the degree of adjustment.
15. 6. In an apparatus of the character described, the combination of a pair of coöperating rolls, an eccentric support for one of said rolls, a gear on said support, a coöperating gear rotatable in opposite directions for imparting rotation to the first mentioned gear and connected support whereby the space between the rolls may be varied, and said rolls being rotatable in their adjusted positions.
20. 7. In an apparatus of the character described, the combination of a rotatable roll, a relatively movable eccentric bushing for the roll adapted in its movement to bodily adjust the roll laterally, a gear connected to the bushing, and a rotatable hand operated gear to engage the first mentioned gear.
25. 8. In an apparatus of the character described, the combination with an annular series of rotatable rolls, of eccentric bushings for a plurality of such rolls, and means operatively associated with all of said bushings whereby the same may be simultaneously rotated to simultaneously adjust the position of the rolls.
30. 9. In an apparatus of the character described, the combination with an annular series of rotatable rolls, of eccentric bushings for a plurality of such rolls, and means operatively associated with all of said bushings for rotating the same at will in opposite directions, whereby all of the connected rolls may be simultaneously adjusted.
35. 10. In an apparatus of the character described, the combination with an annular series of rotatable rolls, arranged in pairs, of eccentric bushings for one roll of each pair, and means operatively associated with all of said bushings whereby the same may be simultaneously rotated to simultaneously adjust the position of the rolls, and indicating means operatively associated with the last mentioned means whereby to determine the degree of adjustment.
40. 11. In an apparatus of the character described, the combination with an annular series of rotatable rolls arranged in pairs, of eccentric bushings for one roll of each pair, and means operatively associated with all of said bushings whereby the same may be simultaneously rotated to simultaneously adjust the position of the rolls, said means including gear teeth on each bushing, and means operatively associated with all of said gear teeth, including a master gear.
45. 12. In an apparatus of the character described, the combination with an annular series of rotatable rolls arranged in pairs, of eccentric bushings for one roll of each pair, and means operatively associated with all of said bushings whereby the same may be simultaneously rotated to simultaneously adjust the position of the rolls, and means for locking the rolls in adjusted positions, said locking means permitting rotation of the rolls.
50. 13. In an apparatus of the character described, the combination of an annular series of rolls arranged in pairs, the rolls of each pair rotating in opposite directions, one of the rolls for each pair having an eccentric bushing, and means common to all of said bushings for simultaneously adjusting its connected roll relative to its coöperated roll.
55. 14. In an apparatus of the character described, the combination of an annular series of rolls arranged in pairs, the rolls of each pair having an intermeshing gear whereby the same will rotate in opposite directions, one of the rolls of each pair having an eccentric bushing, and means for simultaneously moving said eccentric bushings, to simultaneously adjust the rolls connected therewith.
60. 15. In an apparatus of the character described, the combination of an annular series of rolls arranged in pairs, the rolls of each pair rotating in opposite directions, one of the rolls of each pair having an eccentric bushing, a gear on each bushing for rotating the same to adjust the connected roll, and a master gear operatively associated with said gears for simultaneously adjusting said rolls.
65. 16. In an apparatus of the character described, the combination of an annular series of rolls arranged in pairs, the rolls of each pair rotating in opposite directions, one of the rolls of each pair having an eccentric bushing, a gear on each bushing for rotating the same to adjust the connected roll, a master gear operatively associated with said gears for simultaneously adjusting said rolls, and an associated lock for maintaining the parts in adjusted position.

17. In an apparatus of the character described, the combination of an annular series of rolls arranged in pairs, the rolls of each pair rotating in opposite directions, one of the rolls of each pair having an eccentric bushing, a gear on each bushing for rotating the same to adjust the connected roll, and a master gear operatively associated with said gears for simultaneously adjusting said rolls, and means for limiting the movement of the master gear. 75
18. In an apparatus of the character described, the combination of an annular series of rolls arranged in pairs, the rolls of each pair rotating in opposite directions, one of the rolls of each pair having an eccentric bushing, a gear on each bushing for rotating the same to adjust the connected roll, and a master gear operatively associated with said gears for simultaneously adjusting said rolls, said master gear being rotatable in reverse directions whereby to adjust the rolls toward and from one another at will, and means for limiting the movement of the master gear in opposite directions. 85
19. In an apparatus of the character described, the combination of an annular series of rolls, eccentric bushings for the rolls, gear teeth on the bushings, a master gear ring having teeth to engage the bushings, and also having an auxiliary set of gear teeth, and a hand operated rotatable shaft having a pinion to engage the auxiliary gear teeth to rotate the master gear ring and impart rotatable movement to the eccentric bushings. 90
20. In an apparatus of the character described, the combination of an annular series of rolls, eccentric bushings for the rolls, gear teeth on the bushings, a master gear ring having teeth to engage the bushings, and also having an auxiliary set of gear teeth, and a hand operated rotatable shaft having a pinion to engage the auxiliary gear teeth to rotate the master gear ring and impart rotatable movement to the eccentric bushings, and an indicating means operatively associated with said hand operated shaft. 95
21. In an apparatus of the character described the combination of a pair of coöperating rolls arranged side by side, said rolls being adapted to rotate in opposite directions, and means for relatively adjusting one of the rolls relative to the other comprising opposed bushings having eccentric recesses, said rolls having supporting end parts loosely positioned in said eccentric recesses, a rod projecting between the bushings and loosely through said supporting parts and roll, means for locking the rod to the bushings, and a movable part engaging one of said bushings whereby through the medium of the connecting rod to simultaneously rotate both bushings and move the connected roll laterally. 100
22. In a machine of the character de- 130
- scribed, the combination of a rotatable head, a pair of coöperating rolls carried by the head, gear means for rotating one of said rolls in the rotary movement of the head, an eccentric support for the coöperating roll, whereby to adjust the same laterally relative to the first mentioned roll, hand operative gear means for adjustment and independent gear driving connection between the rolls. 75
23. In a machine of the character described, the combination of coöperating rolls mounted for rotatable movement, and means for laterally adjusting one of said rolls relative to the other, comprising eccentric collars at opposite ends of said roll, circular bearings for said rolls, and connected mechanism for simultaneously adjusting said collars in said bearings at the opposite ends of said roll. 80
24. In a machine of the character described, the combination of a plurality of radial pairs of separating rolls, and means for simultaneously adjusting one roll of each pair of rolls laterally with respect to its coöperating roll, said means including an eccentric bearing for one roll of each pair, a gear ring, gears on said eccentric bearings to be engaged by the gear ring, said gear ring being mounted for rotatable movement, and means for maintaining the same in fixed position. 90
25. In a machine of the character described, the combination of rolls radially arranged and operating in pairs, one of the rolls of each pair being provided with an adjusting eccentric bushing at each end, connected mechanism whereby both bushings may be rotated in the same direction at the same time, and whereby all of the adjusting bushings of all of the adjusting rolls are moved in the same direction at the same time. 100
26. In a machine of the character described, having rolls radially arranged and operating in pairs, bushings for one of the rolls of each pair so constructed that both of the ends of said roll may be moved at the same time so as to bring it and its associated roll laterally nearer or farther apart, and common means whereby all of the adjusting rolls and their associated rolls will be brought nearer or farther apart the same distance in the same direction and at the same time by one operation. 110
27. In an apparatus of the character described, the combination of a vertically disposed stationary shaft, a master gear wheel fixed on the shaft, an adjustable gear wheel sleeved upon the shaft, a rotatable head sleeved upon the shaft, a pair of coöperating rolls carried by the head adapted to be driven one from the other, a gear connection between the master gear and one of said rolls, the other roll being mounted for lat- 125

- eral adjustment relative to the first mentioned roll, a gear connection between said other roll and the adjusting gear, and means for moving the said adjusting gear.
28. In an apparatus of the character described, the combination of a vertically disposed stationary shaft, a rotatable casting sleeved upon the shaft for rotatable movement, separating rolls carried by the casting, an adjusting gear sleeved upon the shaft, a master gear fixed upon the shaft at a point above the adjusting gear, a driving connection between the master gear and said rolls, and a gear connection between the adjusting gear and one of said rolls whereby to adjust the same laterally with respect to the cooperating roll.
29. In an apparatus of the character described, the combination of a vertically disposed stationary shaft, a rotatable casting having a sleeved connection with the shaft, a master drive gear fixed upon the shaft, an adjusting member sleeved upon the shaft between the master gear and the connection between the casting and shaft, separating rolls carried by the casting, a gear drive connection between said master gear and the rolls, and means operatively associated with said adjustable member whereby to relatively adjust the rolls, said last mentioned means having an associated indicator means whereby to determine the adjustment.
30. In an apparatus of the character described, the combination of an annular series of rolls, arranged in pairs, said rolls having intermeshing gears whereby the same rotate in opposite directions, one of the rolls of each pair having connected thereto for relative rotatable movement at opposite ends of an eccentric bushing, circular bearings therefor, a gear on the bushing at one end of said rolls, and a master gear operatively associated with said last mentioned gears for simultaneously adjusting said rolls.

In testimony whereof I hereunto affix my signature in the presence of two witnesses.

GEORGE F. CRIPPEN.
